UNITED STATES PATENT OFFICE.

ETHEL L. POST, OF LOS ANGELES, CALIFORNIA, ASSIGNOR TO MUTUAL ORANGE DISTRIBUTORS, OF REDLANDS, CALIFORNIA, A CORPORATION OF CALIFORNIA.

DESIGN FOR AN ADVERTISING PEDESTAL.

Application filed June 25, 1928. Serial No 27,273. Term of patent 14 years.

To all whom it may concern:

Be it known that I, ETHEL L. Post, a citizen of the United States, residing at Los Angeles, county of Los Angeles, State of California, have invented a new, original, and ornamental Design for an Advertising Pedestal, of which the following is a specification, reference being had to the accompanying drawing, forming a part thereof.

The figure is a perspective view of an advertising pedestal showing my new design.

I claim:

The ornamental design for an advertising pedestal, as shown.
